UNITED STATES PATENT OFFICE.

CONRAD GRUNHOW, OF CHICAGO, ILLINOIS.

OUTLET-BOX HANGER.

1,276,904.

Specification of Letters Patent. Patented Aug. 27, 1918.

Application filed October 5, 1917. Serial No. 194,934.

To all whom it may concern:

Be it known that I, CONRAD GRUNHOW, a citizen of the United States, residing at Chicago, in the county of Cook and State 5 of Illinois, have invented certain new and useful Improvements in Outlet-Box Hangers, of which the following is a specification.

This invention relates to improvements in outlet box hangers, and more particularly 10 to a fitting for securing an outlet box to a cleat hanger.

One of the objects of my invention is to provide a fitting which may be readily attached or detached at any desired point on 15 a bar without the necessity of sliding the same over the end of the bar.

Another object of the invention is to provide a fitting which may be readily applied to a bar and fastened in place without the 20 necessity of the workman's using more than one hand in the operation.

A still further object of the invention is to provide a sturdy, rugged, inexpensive construction which will be efficient in operation and adaptable to many different conditions.

Still other and further objects will become readily apparent to those skilled in the art from a consideration of the following 30 description and drawing, wherein:

Figure 1 is a transverse sectional view through a hanger bar, showing two boxes supported on my improved fittings, one being shown in vertical section.

Fig. 2 is a vertical sectional view on the line 2-2 of Fig. 1 on an enlarged scale.

Fig. 3 is a plan view of the fitting shown in Fig. 2.

Fig. 4 is a vertical sectional view through 40 a modified form of fitting.

Fig. 5 is a plan view of the fitting shown in Fig. 4.

Fig. 6 is a vertical sectional view through 45 still another modified form of fitting, and:

Fig. 7 is a plan view of the fitting shown in Fig. 6.

In the drawings, I have shown a preferred embodiment of the invention in Figs. 1, 2, and 3, the other two forms illustrated 50 in Figs. 4 and 5 and Figs. 6 and 7 being modifications thereof.

The outlet box hanger comprises a fitting adapted to be passed through the central opening in the box and carries two upstanding, spaced-apart arms, shaped at their upper ends to permit engagement with a

hanger bar at any desired point without the necessity of longitudinally sliding the same into position.

Referring to the form of fitting shown in 60 Figs. 1, 2, and 3, the numeral 10 indicates the base from which projects upwardly a pair of spaced-apart arms 11 of arcuate planar outline to permit their passage through the circular opening in the center 65 of the outlet box. The opening or space between the arms 11 is approximately equal to the width of the hanger bar 12 and from opposite edges of the upper end portions of the arms 11, I have formed arcuate continuations or wings 13 which extend over the opposite sides of the bar and carry at their ends downwardly extending prongs or hooks 14, for engagement with the openings 15 in the bar. The distance between the 75 end of each prong 14 and the edge of the opposite arm 11, is somewhat greater than the thickness of the bar 12 so as to permit the removal of the fitting by lifting it up and turning it sidewise upon the bar. A 80 reversal of the operation permits the attachment of the fitting with its box to any selected position upon the cleat bar.

A flat plate 16 extends through the space between the upstanding arms 11 and at its 85 outer ends is flanged over to provide prongs 17 which extend over the edges of the arms 11 to hold the plate in place preventing its displacement without interfering with its free vertical movement within the opening. 90 The ends of the plate bear against the under side of the box and hold it up against the cleat bar. The lower end of the base 10 extends downwardly as at 18 and is threaded to receive a fixture indicated in dotted 95 lines at 19 in Fig. 1. The threaded lower end is provided with a counter sunk recess 20 to receive the head 21 of the screw 22 which takes through the wall of metal in the base 10 at the bottom of the recess 20. 100 This screw is of sufficient length so that when the head 21 is within the recess 20, the upper end of the screw will bear against the plate 16 which lies below and inside the outlet box 23 and presses the same upwardly 105 into engagement with the cleat bar 12 preventing its disengagement from the prongs 14 of the fitting.

The attachment or detachment of an outlet box to a cleat bar is very simple with this 110 form of fitting and may be accomplished with one hand, a feature of importance when

doing overhead work as in putting up outlet boxes for ceiling lights. The screw 22 is run out far enough to bring the plate 16 near the bottom of the space between arms 5 11—11. The fitting is then pushed through the opening in the top of the outlet box and the workman can then hold the fitting in one hand and reach up to the cleat bar which may have already been nailed in place. The 10 fitting is held horizontal, and its open end slid over the side of the bar until the hooks 14 are beyond the edge of the bar. The fitting is then swung down into a vertical position and the hooks 14 positioned in the openings 15 in the bar. These openings are positioned at convenient places throughout the length of the bar to receive attaching nails or the stove bolts used in some types of hangers. The workman may then remove 20 his hand, and the box will remain in its selected position. With the same hand he can then take a screw driver and tighten up screw 22 which clamps the parts together preventing withdrawal of the hooks 14.

25 This same type of hanger may be used either with a deep outlet box with knock outs in the sides as indicated at 23 in Fig. 1, set in an offset portion of the cleat bar, or with a shallow box as at 24 for attachment 30 to the straight part of the bar. In either event the fitting can be attached or detached by simply hooking or unhooking it over the side of the bar, a decided advantage over studs which are slideable upon a bar and can 35 only be attached or detached by sliding over an end of the bar, or cannot be removed at all as in the case of a stud positioned in an offset bent portion of a bar.

In Figs. 4 and 5, I have illustrated a modification in which the fitting is formed from 40 a straight bar of metal bent into U form, the upstanding arms 30—30 being swedged into arcuate cross-section to permit threading of the bottom portion as at 31 and to permit the 45 upper portion to extend through the circular opening in the outlet box 32. Diametrically opposite holes are drilled in the upper ends of the arms to receive a nail 33 of the same size as is used in attaching the cleat bar to 50 the floor beams. A plate 16 formed with hooks 17 identical with the one heretofore described, is positioned beneath the box and is clamped into box holding position by means of a screw 34 taking through the base 55 of the hanger.

In Figs. 6 and 7 still another variation is shown in which the arms 40 project upwardly from the threaded base 41, and are provided at each side near their upper ends 60 with ears 42 which overlie the edge portions of bar 12 when in the position shown in Fig. 6. The ears 42 are spaced apart a distance sufficient to permit the hanger's being hooked sidewise over the edge of the bar.

65 The standard form of outlet box is pro-

vided with a central opening to receive a hanger and with two pairs of diametrically opposite, spaced-apart bolt holes 43 arranged to receive the bolts used with one type of hanger now on the market. In Figs. 6 and 7, 70 I have shown the plate 44 formed with extensions 45 from the ends of which depend tongues 46 for engagement with an opposite pair of box openings 43 to prevent relative rotation of the box and hanger. The lips 47 75 extend from the sides of the washer as in the previously described instances to prevent removal of the plate from the hanger.

Whereas I have illustrated and described a preferred form of the invention with two 80 possible modifications, it will be apparent to those skilled in the art that many changes and modifications may be made, therein, without departing from the spirit of the invention or the scope of the appended claims. 85

Having described my invention, what I claim is:—

1. An outlet box hanger, comprising a bar, a fitting adapted to pass through an opening in the box, and having a vertical opening in 90 its upper end portion to receive the bar, a plate vertically slideable within the opening in the fitting and adapted to be positioned beneath the opening in the box, and a screw taking axially through the lower end of the 95 fitting for engagement with said plate to force the same against the box.

2. An outlet box hanger comprising a bar, a fitting adapted to pass through an opening in the box and having a vertical opening in 100 its upper end portion to receive the bar, a plate vertically slideable within the opening in the fitting and adapted to be positioned beneath the opening in the box, projections on the plate to prevent its removal from the 105 fitting, and a screw taking axially through the lower end of the fitting for engagement with said plate to force the same against the box.

3. In combination with an outlet box having an opening, a hanger comprising a bar, a fitting adapted to pass through an opening in the box and having a vertical opening in its upper end portion to receive the bar, a plate vertically slideable within the opening in the fitting, and adapted to be positioned beneath the opening in the box, said box having diametrically opposite openings at each side of the opening through which the fitting passes, prongs carried by the plate 110 for engagement with the diametrically opposite openings, and a screw taking axially through the lower end of the fitting for engagement with said plate to force the same 115 against the box. 120

4. An outlet box hanger comprising a bar, a fitting adapted to pass through an opening in the box, said fitting having upwardly extending spaced-apart arms, means on the 125 ends of the arms for engagement with the 130

bar, a plate positioned within the space between the arms, and adapted to underlie the box, and a screw taking through the bottom of the fitting for engagement with the plate 5 to clamp the parts together.

5. An outlet box hanger comprising a bar, a fitting adapted to pass through an opening in the box, said fitting having upwardly extending spaced-apart arms, means carried 10 on the upper ends of the arms and spaced-apart a distance greater than the smallest transverse dimension of the bar but less than the largest transverse dimension of the bar for engagement with the top of the bar when 15 at right angles to its greater width, a plate positioned within the space between the arms and adapted to underlie the box, and a screw taking through the bottom of the fitting, for engagement with the plate to clamp 20 the parts together.

6. An outlet box hanger comprising a bar having spaced-apart openings therein, a fitting adapted to pass through an opening in the box, said fitting having an upstanding 25 arm, a hook projecting from the arm for engagement with an opening in the bar, and means carried by the fitting for clamping the box against the bar.

7. An outlet box hanger comprising a bar 30 having spaced-apart openings therein, a fitting adapted to pass through an opening in the box, said fitting having upstanding arms to lie at each side of the bar, a hook projecting from an arm for engagement with an 35 opening in the bar, and means carried by the fitting for clamping the box against the bar.

8. An outlet box hanger comprising a bar 40 having spaced-apart openings therein, a fitting adapted to pass through an opening in the box, said fitting having upstanding arms to lie at each side of the bar, a hook projecting from an arm for engagement with an 45 opening in the bar, a plate positioned between the arms and adapted to underlie the

box, and a screw taking through the bottom of the fitting for engagement with the plate for clamping the box against the bar.

9. An outlet box hanger comprising a bar having spaced-apart openings therein, a fitting 50 adapted to pass through an opening in the box, said fitting having upstanding arms to lie at each side of the bar, a hook projecting from each arm at opposite sides of the fitting for engagement with a pair of openings in the bar, a plate positioned between the arms and adapted to underlie the box, and a screw taking through the bottom of the fitting for engagement with the plate to press the plate box and bar together, preventing withdrawal of the hooks from the 55 openings in the bar.

10. An outlet box hanger comprising in combination, a bar, a fitting adapted to connect a fixture thereto, said fitting having a 60 pair of arms spaced apart and adapted to receive said bar, means for holding said bar therein, a plate slideable in the space between said arms, and means engaging said plate to clamp the fitting against said bar. 70

11. An outlet box hanger comprising in combination, a stationary bar, a fitting adapted to secure a fixture thereto, said fitting having a pair of arms spaced apart a distance greater than the largest transverse 75 dimension of the bar to receive the same, each of said arms having an extension, which extensions are spaced apart from each other a distance slightly greater than the smallest transverse dimension of the bar, so that the fitting may be positioned in coöperative relation to the bar, by moving the fitting onto the bar in one plane and then turning it so that the bar rests in the space beneath said extensions of said arms, and 80 means for clamping said fitting to said bar. 85

In testimony whereof I hereunto set my hand.

CONRAD GRUNHOW.
